UNITED STATES PATENT OFFICE.

FREDERIC S. BUTLER, OF SAN FRANCISCO, CALIFORNIA.

DESIGN FOR A TYPOGRAPHIC VIGNETTE.

SPECIFICATION forming part of Design No. 19,342, dated October 8, 1889.

Application filed August 6, 1889. Serial No. 319,947. Term of patent 14 years.

To all whom it may concern:

Be it known that I, FREDERIC S. BUTLER, a citizen of the United States, residing in the city and county of San Francisco, and State of California, have invented and produced a new and original Design for a Typographic Vignette, of which the following is a specification, reference being had to the accompanying drawing, forming part thereof.

10 The leading features of my design consist in the pictorial representation of an eagle with raised pinions perched on a shield that bears on its field the "Stars and Stripes" arranged in the usual form. Behind the shield and partly covered by it is displayed the American flag, with the field of stars showing at the upper right-hand corner of the shield, but almost concealed from view behind that portion of the shield, while the outer end of the flag is

15 brought to the front in folds that partially conceal the bottom of the shield. The eagle is represented principally in side view, but both pinions in sight, and the shield and flag are oblique to the plane of the picture.

The background of the design represents 25 light clouds.

This vignette can be printed in one color or in several colors, after the manner of printing designs in colors now practiced and followed in the art. It can also be produced in 30 different sizes, according to the space allowed.

What I claim is—

The design for a typographic vignette herein shown and described, the same comprising the representation of an eagle with 35 raised pinions perched on a shield bearing the Stars and Stripes, with the American flag behind and partly concealed by the shield, arranged on a background of clouds.

In testimony that I claim the foregoing I 4c have hereunto set my hand and seal.

FREDERIC S. BUTLER. [L. S.]
